UNITED STATES PATENT OFFICE.

GROVER R. REEVES, OF LATAH, WASHINGTON.

IRONING TABLE.

Application filed March 17, 1928. Serial No. 262,425.

This invention relates to ironing tables and to that class in which the ironing board is clamped upon a table by a clamping action existing between the inner end of the 5 board itself and the leg of the board.

The general object of the present invention is to improve upon a construction of this character by providing an ironing board and support therefor which has an 10 auxiliary or shirt board adapted to be turned into operative position parallel to the main ironing board but in spaced relation thereto or turned over backward over the table and out of the way of the main 15 ironing board entirely.

A further object is to provide means whereby the auxiliary board is held against any lateral movement or against any strain which would otherwise be placed against 20 the hinges.

My invention is illustrated in the accompanying drawings, wherein:—

Figure 1 is a side elevation of an ironing table constructed in accordance with my invention;

Figure 2 is a longitudinal sectional view thereof;

Figure 3 is a front view thereof;

Figure 4 is a fragmentary top plan view 30 with the auxiliary table turned back.

Referring to this drawing, 10 designates the main ironing board, the rear end of which is longitudinally slotted as at 11, the front wall of this slot being downwardly 35 and forwardly inclined as at 12. Pads 13 are mounted upon the upper face of the ironing board at the rear end thereof on each side of the opening 11.

Co-operating with the ironing board is a 40 leg 14 rectangular in cross section and having its upper end disposed at less than a right angle to the longitudinal axis of the leg. This upper end is reduced in thickness so as to form an upwardly extending rib 45 15. The leg has attached to it the cross bar 16 having a width equal to the width of the ironing board, this cross bar being set into a notch in the inner face of the leg. Hinges 17 are attached to this cross bar and to the 50 under face of the table. The rear portion of the board is adapted to rest against stops, strips or blocks 18 attached to the side faces of the leg, these stops having their upper

edges inclined with relation to the longitudinal axis of the leg, that is, disposed 55 parallel to the normal horizontal position of the board 10 when the latter is in operative position. The leg above the main ironing board is formed with a right angular notch or recess 19, the inner face of which is 60 padded as at 20 and this recess is adapted to engage a table top A so that the table top will be gripped as between jaws between the rear end of the ironing board and the upper wall of the notch 19.

The upper end of the leg is formed to provide the laterally projecting shoulders or ribs 21 and hinged to the rear face of the leg at the upper end thereof are the hinge leaves 22, one of which is attached to the 70 auxiliary ironing or shirt board 23. This is grooved at its under face as at 24 to fit upon the longitudinally extending rib 15 and thus be held against any lateral movement which would put strain upon the 75 hinges. When this auxiliary board is turned over into parallel relation to the main ironing board 10, it acts as a shirt board upon which shirts and other like articles may be readily ironed but this shirt board may be turned backward upon the table whenever 80 it is desired to have the ironing board entirely free.

Obviously minor changes might be made without departing from the spirit of the invention.

I claim:

An ironing table comprising an ironing board having a longitudinally extending slot at its rear end, a leg extending downward through said slot, the leg being formed with 90 a cross bar, hinges on each side of the leg and connecting the cross bar to the under face of the ironing board, the leg having laterally projecting shoulders rearward of the cross bar, the ironing board being adapted 95 to be turned from parallel into angular relation to the leg, the portion of the leg above the ironing board being formed with a recess in its rear face which, with the rear end of the ironing board, is adapted 100 to receive and clamp a table.

In testimony whereof I hereunto affix my signature.

GROVER R. REEVES.
